UNITED STATES PATENT OFFICE.

OTTO HOFFMANN, OF MANCHESTER, ENGLAND.

DESIGN FOR A HUMIDIFIER-CASING.

SPECIFICATION forming part of Design No. 22,706, dated August 15, 1893.

Application filed June 27, 1893. Serial No. 478,988. Term of patent 7 years.

To all whom it may concern:

Be it known that I, OTTO HOFFMANN, engineer, a subject of the Emperor of Germany, residing at 17 Duke Street, Greenheys, Manchester, England, have invented a new and original Design for Humidifier-Casings, of which the following is a specification.

The design relates to the configuration of casings for humidifiers and is shown in the accompanying drawing. The body portion *b* of the casing is cylindrical and at its lower end a flange *e* extends outwardly and downwardly and below this there is an upwardly inclining flange *g* with its edge extending adjacent to the edge of the flange *e*. A space is left between the edges which is crossed or interrupted by porters *f* which serve to connect

the lower flange with the upper and thus one flange supports the other. Below the flange *g* there is a second cylindrical part *b'*. 20

The essential feature of my design is the upper and lower cylindrical parts with the inclined flanges between, said flanges being separated by a space crossed by pieces *f*.

I claim—

The design for humidifier casings herein described and shown.

In witness whereof I have hereunto set my hand in presence of two witnesses.

OTTO HOFFMANN.
